(57) **ABSTRACT**

A precast vertical reinforcement concrete cube retaining wall having blocks of precast concrete used as earth and water retaining walls, with vertical steel reinforcement and water-proofing features. It provides an alternative to substitute traditional cast-in-place concrete walls. The wall allows for rapid installation without scaffolding and formwork, reduces construction materials, takes less time and labor, and greatly reduces the cost of wall construction. After installation of the wall in one row, concrete grout is poured in each joint for homogeneous connection, similar to the cast-in-place wall installation. After completing the top row, vertical steel bars are inserted in each hole, connected with starter foundation bars, and filled with the concrete grout.

**PRECAST VERTICAL REINFORCEMENT
CONCRETE CUBE RETAINING WALL AND
MOLD**

FIELD OF THE INVENTION

The present invention pertains generally to retaining walls, and specifically the invention relates to a precast vertical reinforcement concrete cube used as an earth and water retaining wall.

BACKGROUND OF THE INVENTION

The construction of reinforced concrete retaining walls still use traditional cast-in-place methods, including form-work, scaffolding, and other materials, causing significant material waste.

It takes a long time to construct the wall, including the time for concrete curing and hardening. It requires significant labor, and a substantial construction budget.

The main purpose of this invention is to modify the product form and the installation method to provide an product alternative that reduces construction material consumption, lowers labor costs, reduces construction time, and saves on construction budgets. However, the benefits of the disclosed precast vertical reinforcement concrete cube retaining wall are the same, providing similar quality and performance as a cast-in-place type of concrete wall.

BRIEF DESCRIPTION OF THE DRAWINGS

In the following detailed description, reference will be made to drawings comprised of the following figures:

FIG. 1 is a perspective view of a precast vertical reinforcement concrete cube retaining wall.

FIG. 2 is a plan view of the precast vertical reinforcement concrete cube retaining wall.

FIG. 3 is a front view of the precast vertical reinforcement concrete cube retaining wall. FIG. 4 is a left side view of the precast vertical reinforcement concrete cube retaining wall.

FIG. 5 is a cross-sectional view of first row blocks for precast vertical reinforcement concrete cube retaining wall installed on foundation.

FIG. 6 is a cross-sectional view of top row blocks for the precast vertical reinforcement concrete cube retaining wall.

FIG. 7 is a perspective view of the precast vertical reinforcement concrete cube retaining wall showing the installation on the foundation.

FIG. 8 is a plan view of a starter bar locator template on the top of the steel-reinforced foundation for the precast vertical reinforcement concrete cube retaining wall.

FIG. 9 is a perspective view of mechanical couplers with cones connected with the starter bars of the foundation for the precast vertical reinforcement concrete cube retaining wall.

FIG. 10 is a perspective view of vertical shear rods laid on the base of hollow cubes connected between each precast vertical reinforcement concrete cube retaining wall.

FIG. 11 is a perspective view of an adjuster kit for adjusting precast vertical reinforcement concrete cube retaining walls.

FIG. 12 is an exploded plan view of a mold assembly showing four vertical panels of the mold assembly for casting different concrete faces of the precast vertical reinforcement concrete cube retaining wall.

2

FIG. 13 is a perspective view of front and rear panels of the mold assembly for casting top and bottom concrete faces of the precast vertical reinforcement concrete cube retaining wall.

FIG. 14 is a perspective view of left and right panels of the mold assembly for casting left and right side concrete faces of the precast vertical reinforcement concrete cube retaining wall mold.

FIG. 15 is a perspective view of the mold assembly showing four panels for casting the precast vertical reinforcement concrete cube retaining wall.

DISCLOSURE OF THE INVENTION

FIG. 1, FIG. 2, FIG. 3 and FIG. 4, show a precast vertical reinforcement concrete cube retaining wall 1, which is the an embodiment of a concrete cube, having three dimensional space and solid shape, comprised of six square faces of a cube having equal length, breadth, and height. The six square faces of the wall 1 include a top front face 2, a rear face 3, a top face 4, a bottom face 11, a left side face 18, and a right side face 23. The front face 2 and rear face 3 of the wall 1 are smooth surfaces. The top face 4 contains a rectangular male interlocking 5, length thereof is parallel to and not more than half of a front upper edge 6. The breadth of the rectangular male interlocking 5 is parallel to and not less than twenty-five percent of a left upper edge 7. There are two rows parallel to the front upper edge 6: a first row 8 and a second row 9. The wall 1 has a plurality of round holes 10 placed vertically in rows 8 from the top face 4 to the bottom face 11. The number of round holes 10 in a row is at least five holes, and the diameter of each hole 10 does not exceed ten percent of the front upper edge 6. Each round hole of the second row 9 has a counterbore 12 at the same center. The diameter of the counterbore 12 is not less than fourteen percent and the depth thereof is not less than five percent of the front upper edge 6.

In the first row 8, the center of each hole 10 has an irregular circumference of the counterbore 12 and a straight line 13, with a depth equal to that of the second row 9 as shown in FIG. 2. On the opposite side, there are two rows parallel to the rear upper edge 14, and the number of holes and their positions are the same as on the front upper edge 6. At half of the left upper edge 7, and parallel to the front upper edge 6, a pair of lifting plates 15 is provided. The center line of the plates 15 is parallel to the front upper edge 6, and their position is at half of the left upper edge 7 between the rectangular male interlocking 5.

On the bottom face 11, a pair of covers 16 is provided for receiving the lifting plates 15. The pair of covers 16 is located on the bottom face 11 at the same center in the opposite direction as of the top face 4 having the lifting plates 15 and a rectangular female interlocking 17. The sizes and positions are the same as the rectangular male interlocking 5, wherein the rectangular female interlocking 17 is configured to receive the rectangular male interlocking 5, thereby allowing both the rectangular male 5 and female 17 interlockings to fit together. The bottom face 11 also comprises holes 10 and other features same as the front face 4.

The left side face 18 has a vertical male interlocking 19, position thereof is at half of the left upper edge 7, and the breadth is not less than twelve percent of the left upper edge 7 with a protruding taper tip, whose length is the same as the breadth. The height of the vertical male interlocking 19 extends from the top face 4 to the bottom face four 11. There are smooth surfaces 20, positions thereof are on the left and right sides of the vertical male interlocking 19, and both are

close to the left and right edges. The breadth and height of the smooth surfaces **20** are equal to the vertical male interlocking **19**. The spaces between the smooth surfaces are two grooves **21** positioned between the left and right smooth surfaces **20**. The breadth of them not less than sixteen percent of the left upper edge **7**. The height of the smooth surfaces **20** and grooves **21** is equal to the height of the vertical male interlocking **19** and the depth of the grooves **21** is equal to the breadth of the smooth surfaces **20**. At half of the height on the left side face **18** and at four sides of the four smooth surfaces **20**, four hollow cubes **22** are provided. The hollow cubes **22** are vacant and their length, breadth, and height are equal to the breadth of the smooth surfaces **20**.

On the opposite side of the left side face **18**, a vertical female interlocking **24** is provided at half of a right side upper edge **25** on the right side face **23**. The sizes, shapes, position, and height of the vertical female interlocking **24** are all the same as the vertical male interlocking **19**. The vertical female interlocking **24** is arranged to snugly fit with the vertical male interlocking **19**. The hollow cubes **22** of the right side face **23** have same positions, sizes, and number same as the left side face **18**.

As shown in FIG. 5, FIG. 6, FIG. 7, FIG. 8, FIG. 9, FIG. 10, and FIG. 11, the following steps describes the installation process for the precast vertical reinforcement concrete cube retaining wall **1**:

First step: The installation process begins by constructing a reinforced concrete foundation **26** to support the precast vertical reinforcement concrete cube retaining wall **1** by placing a plurality of starter bar locator templates **27**, consisting of a square steel plate **27a** welded with a round tube **27b** and adjust screws **27e**. These starter bar locator templates **27** are locked on the top of the steel reinforced rods of the foundation **26**, and the starter bars **28** are inserted into the round tubes connected to the steel reinforced rods of the foundation **26**. Each upper end of the starter bars **28** is threaded.

The first precast vertical reinforcement concrete cube retaining wall **1** is lifted to lay it on the reinforced concrete foundation **26**, controlling each round hole **10** to match with each starter bar **28** as mentioned above. Then lift the second precast vertical reinforcement concrete cube retaining wall **1** and lay it on the reinforced concrete foundation **26**, thereby placing the vertical female interlocking **24** close to the vertical male interlocking **19** or the vertical male interlocking **19** close to vertical female interlocking **24**. Further, a pair of blocks is tightened using the adjuster kit **29** for the precast vertical reinforcement concrete cube, by inserting a pair of mounting-cores **29a** into the round holes **10** of both blocks on both sides, front and rear sides respectively, and turning the screw driver **29b** to adjust and hold them in place. Next, mechanical couplers are connected with cones **30**, which consist of mechanical couplers **30a** having upper and lower internal threads. The upper end has a slot for assembling the mechanical coupler, connecting it with the threaded end of the starter bars **28** in each round hole **10** tightly, and has a perforated sheet metal cone **30b** welded to the upper mechanical coupler.

Further, four vertical shear rods **31** are installed into the two rectangle openings **32**, laying them on the base at both sides, left and right, of the hollow cubes at two places. The vertical shear rods **31** consist of steel bars **31a**, with no fewer than two pieces welded with double steel plates **31b**. Continue this process until the end of the first row on the foundation **26**, then pour concrete grout from the rectangular

openings to each left and right hollow cube and continue filling the rectangular openings until full, thereby completing the first step.

Second step: Install the upper and second row by lifting the first precast vertical reinforcement concrete cube retaining wall **1** down to place it on the lower block, where the rectangle female interlocking **17** of the bottom face **11** is placed on the lower rectangular male interlocking **5** of the top face **4** firmly. From this, the first block with the vertical male interlocking **19** is installed to the left direction, then the second precast vertical reinforcement concrete cube retaining wall **1** is lifted down to place it on the second block at the lower part of the first row. The vertical female interlocking **24** is placed close to the vertical male interlocking **19** and the rectangular female interlocking **17** is placed on the rectangular male interlocking **5** firmly. A pair of blocks are adjusted to be closed as mentioned above. The vertical shear rods **31** are laid on the base of the hollow cubes of the rectangular openings **32** as mentioned above.

Third step: Continue installing each row of the wall **1** using this process until reaching the top row of the project. The aforementioned process is continued until the end of the wall is completed. Further, the vertical rebars **33** with lower threaded ends are placed into each round hole **10**, thereby connecting them with the mechanical couplers with cones **30** at the bottom of round holes firmly. The cement grout is poured into each hole completely, preparing to construct a reinforced concrete slab **34** to be placed on the top of the wall. This completes the wall installation process.

FIG. 12 shows an exploded plan view of a mold assembly **40** comprising four vertical molding panels, including a front panel **35**, a rear panel **36**, a right panel **37** and a left panel **38**, provided for casting four vertical concrete faces of the precast vertical reinforcement concrete cube retaining wall **1**.

The four vertical mold panels **35**, **36**, **37**, **38** of the mold assembly are provided to cast different parts of the wall **1**, wherein the right panel **37** is a female mold for casting the left side face **18** of the wall **1** which has a vertical male interlocking **19**, the left panel **38** is a male mold for casting the right side face **23** of the wall **1** which has a vertical female interlocking **24**, and the front panel **35** and the rear panel **36** are used for casting the front face **4** and the bottom face **11** of the precast concrete cube wall **1**, respectively.

FIG. 13 shows a perspective view of the front panel **35** and the rear panel **36** of the mold assembly, provided for casting front face **4** and the bottom face **11** of the wall **1**. Similarly, FIG. 14 shows a perspective view of the right panel **37** and the left mold panel **38**, provided for casting the left side **18** and right side **23** faces of the wall **1**.

As shown in FIG. 14, the right panel **37** comprises different molding members to cast corresponding portions of the left side face wall **18**, including the vertical male interlocking **19**, smooth surfaces **20**, four hollow cubes **22**, two grooves **21** of the left side face **18** of the wall **1**. Similarly, the configuration of the left panel **38** is provided with different molding members corresponding to the right panel **37** except the male mold member to cast corresponding portions of the right side face **23** of the wall **1**. Unlike the female interlocking molding member of the right panel **37**, the male mold member of the left panel **38** enables casting of the vertical female interlocking **24** on the right side face **23** of the wall **1**.

FIG. 15 is a perspective view of the mold assembly **40** showing all four vertical mold panels **35**, **36**, **37** and **38**, provided for casting the four corresponding vertical concrete faces **4**, **11**, **18** and **23** of the precast vertical reinforcement

5

concrete cube retaining wall 1. The mold assembly 40 consists the four panels assembled into a cube: the rectangular front panel 35 is bolted to the square right face panel 37, followed by the square left face panel 38, and finally the rectangular rear panel 36, which is bolted to both side panels 37 and 38.

The front panel 35 of the mold assembly includes a member 10a to cast at least ten round holes 10 and a female interlocking mold member 35a to cast the male interlocking 5 on the top face 4 of the wall 1. Further, the rear panel 36 includes a member 10a similar to the member 10a of the front panel 35, except the male interlocking mold member 36a which is provided to cast the female interlocking 17 on the bottom face 11 of the wall 1. The right 37 and left 38 panels include mold members 37a and 38a to cast different sections of the left side 18 and right side 23 faces of the wall 1, respectively. For instance, as shown in FIG. 15, the mold member 37a of the right panel 37 of the mold assembly is provided to cast the corresponding sections including the vertical male interlocking 19, smooth surfaces 20, four hollow cubes 22, two grooves 21 on the left side face 18 of the wall 1. Similarly, a mold member 38a of the left panel 38 of the mold assembly is provided to cast the corresponding sections including the vertical female interlocking 24, smooth surfaces 20, four hollow cubes 22, two grooves 21 on the right side face 23 of the wall 1.

The invention claimed is:

1. A precast vertical reinforcement concrete cube retaining wall, the wall comprising:

a concrete cube having a three-dimensional, solid shape, comprising six square faces including a front face, a rear face, a top face, a bottom face, a left side face, and a right side face, wherein the length, breadth, and height of the six faces are the same; 30 wherein the front face and rear face have smooth surfaces;

wherein the top face comprises a rectangular male interlocking feature, and the length of the rectangular male interlocking feature is parallel to and not more than half of the length of a front upper edge, the breadth is parallel to and not less than twenty-five percent of the length of a left side upper edge, and the thickness not less than eight percent of the length of the front upper edge; 40

wherein the bottom face has a rectangular female interlocking feature, wherein the size, shape, and position of the rectangular female interlocking feature are the same as the rectangular male interlocking feature on the top face; 45

wherein the top face comprises at least two rows parallel to the front upper edge, a first row, and a second row, each row having round holes placed vertically from the top face to the bottom face, wherein the number of round holes in each row is not less than five, and the diameter of each hole is not 50 exceeding ten percent of the length of the front upper edge;

6

wherein each round hole of the second row has a counterbore at the same center, and the diameter of the counterbore is not less than fourteen percent of the length of the front upper edge and the depth is not less than eight percent of the length of the front upper edge; wherein each round hole of the first row has a counterbore

with an irregular circumference that is partially round and partially a straight line, and the depth is the same as that of the counterbore of the second row;

wherein the top face comprises two rows parallel to a rear upper edge, wherein the holes in the rows parallel to the rear upper edge are symmetrical to the holes in the rows parallel to the front upper edge;

wherein at a middle of the left side upper edge and a right side upper edge, and parallel to the front upper edge, the top face has a pair of lifting plates;

wherein on the bottom face a pair of covers are positioned are vertically aligned with the lifting plates on the top face;

wherein the left side face comprises a vertical male interlocking feature, and the position of the vertical male interlocking feature is at a middle of the left side upper edge, the breadth not less than twelve percent of the length of the left side upper edge, with a protruding taper tip, having length a double the breadth, and a height extending from the top face to the bottom face; wherein the left side face has smooth surfaces positioned

on the left and right side of the vertical male interlocking feature, and the breadth and height of the smooth surfaces are equal to the vertical male interlocking feature;

wherein the left side face comprises a plurality of grooves, positioned between the left and right smooth surfaces, wherein the breadth of the grooves is not less than sixteen percent of the length of the left side upper edge, the height is equal to the height of the vertical male interlocking feature, and the depth is equal to the breadth of the smooth surfaces;

wherein at half of the height of the left side face, and on both sides of the smooth surfaces, the left side face comprising four hollow cubes, wherein the length, breadth, and height of each hollow cube are equal to the breadth of the smooth surfaces;

wherein the four hollow cubes are on the left side face, positioned at the left and right of the smooth surfaces; wherein the right side face comprises a vertical female interlocking feature, positioned at a middle of the right side upper edge, and the size, shape, and height of the vertical female interlocking feature are the same as the vertical male interlocking feature on the left side face; wherein the vertical female interlocking feature is configured to fit on the vertical male interlocking feature; and

wherein the right side face comprises hollow cubes that have positions, sizes, and quantities that are the same as those on the left side face.
